UNITED STATES PATENT OFFICE.

ARTHUR J. PAIGE, OF HIGHLAND PARK, MICHIGAN.

INTERNAL-COMBUSTION ENGINE.

Application filed June 18, 1923. Serial No. 646,180.

To all whom it may concern:

Be it known that I, ARTHUR J. PAIGE, a citizen of the United States, residing at Highland Park, in the county of Wayne 6 and State of Michigan, have invented a new and useful Internal-Combustion Engine, of which the following is a specification.

The object of my invention is to produce 10 a compact motor, preferably of the internal combustion type, though capable of use in connection with steam or other similar motive fluid.

The accompanying drawings illustrate 15 my invention.

Fig. 1 is a side elevation of my improved motor, with portions in vertical sections, the upper left hand corner being a section on line 1 of Fig. 2, while the upper right 20 hand portion is a section on line 1^a of Fig. 2;

Fig. 2 is an elevation at right angles to Fig. 1, the upper part being in axial vertical section and a portion of the lower 25 part being also in vertical section;

Fig. 3 a side elevation, on a smaller scale, and Fig. 4 an elevation opposite to that shown in Fig. 3.

In the drawings 10 indicates a stationary 30 casing having a circumferential annular chamber 11 having parallel ported opposed faces 12 and 13 between which is fitted a rotary cylinder body 14 which is provided with parallel ported faces co-acting with 35 the ported faces 12 and 13 and which is formed of a plurality of segments mated upon radial lines as indicated at 15.

In the present drawings I have shown the 40 rotary cylinder body, or rotor, as formed of two mating segments, the engine being of a four cylinder type, but it will be readily understood that one or more pairs of additional cylinders may be provided, in which case the rotor will be composed of 45 a correspondingly greater number of segments.

Formed in each rotor segment are two cylinders 16 (only one cylinder of the segment being shown) said cylinders having 50 their axes arranged tangentially to the axis of the rotor and having one end opening into a radial face of the segment, the arrangement being such that two cylinders of mating rotor segments will lie end to end, 55 as shown in Fig. 1. The two cylinders of

each pair of cylinders are preferably arranged so that their axes lie at an obtuse angle to each other, as indicated in Fig. 1, for a purpose which will appear.

Mounted in each cylinder is a piston 17 60 provided with a pitman 18 and the two pitmen of adjacent pistons are pivotally connected to the outer end of a lever 19 pivoted at 20 in the rotor 14.

The rotor 14 is connected to a shaft 21 65 journaled in suitable bearings, centrally, in the casing 10. Lever 19, between its fulcrum and outer end, is provided with two oppositely extending arms 22 and 23. Arm 22 carries a cross-pin 24 which is projected 70 through openings 25 formed through the side walls of the adjacent rotor segment and the outer ends of this cross-pin carry pairs of rollers 26 which, in the present drawings, are shown as supported upon roll- 75 er bearings 27.

Similarly, arm 23 carries a cross-pin 28 projected through the side walls of the adjacent rotor segment and provided at its ends with pairs of rollers 29. 80

Surrounding shaft 21, and carried by casing 10, are two cams 31 and 32 upon which rollers 26 and 29 ride. There is a very slight variation, theoretically, between the proper cam which will always be contacted by the leading rollers 26, and a cam which will always be contacted by the trailing rollers 29, but for short piston strokes, the cams may be modified from theoretical correctness so as to co-act with both such 90 rollers. If desired, however, the two cams may be formed with two slightly different tracks of such character that some of the rollers of each set will contact with the cam during the strokes of their pistons in 95 one direction, while the other rollers of the set will contact with the cam during the other strokes of their pistons.

The ports 35, through wall 12, are inlet ports and are connected with a suitable inlet manifold 36, through which the motive fluid is delivered to the cylinders. The ports 37, through wall 13, are exhaust ports and deliver to exhaust pipes, or exhaust manifold, 38. 100

The side walls of the rotor, within the annular chamber 11, are continuous, except for the ports 40, one for each cylinder, leading into the outer end of the cylinder, and each of said ports is suitably protected 110

by packing rings 41 conveniently in the manner disclosed in my re-issued patent No. 14,347.

Motive force is applied alternately to the 5 pistons of each pair of cylinders and the cams 31 and 32 are so designed that motive force applied to the trailing piston of each pair will drive the rollers 26 inwardly and forwardly upon the cams so as to cause 10 the rotor to be drawn forwardly in the direction indicated by the arrow in Fig. 1. Motive force applied to the leading piston of each pair will drive the trailing rollers 29 inwardly upon the cams, thereby exerting 15 a forward push upon the rotor body. If a motive fluid such as steam is used, it will be apparent that rollers 29 and 26 will exert alternate pulls and pushes upon the cams and rotor to cause continuous rotation 20 of the rotor, whereas, if an explosive motive fluid is used, it will be apparent that, immediately following the exertion of force upon the cams through rollers 26, continued rotation of the rotor, under the momentum of 25 the parts, will cause rollers 26 to be swung outwardly by the cams so as to produce suction in the leading cylinder of the pair under consideration and exhaust in the trailing cylinder of that pair. Ultimately, ex- 30 plosion in the leading cylinder of a pair will cause co-action between rollers 29 and the cams, in the manner already described, to exert a propulsive force upon the rotor. By setting the axes of each pair of cylin- 35 ders at an obtuse angle, as indicated in Fig. 1, the power exerted upon the lever 19 by each of the pistons, at the beginning of the power stroke is substantially at right angles to the lever.

40 I claim as my invention:

1. In an engine, the combination of a shaft, a cylinder body carried by said shaft and provided with a pair of cylinders, each of which is arranged substantially perpendicular to a radius of the rotor and ported laterally for the induction and eduction of motive fluid, pistons mounted in the cylinders of said cylinder body, a lever pivoted in the cylinder body and connected to said 45 pair of pistons, a casing enclosing said cylinder body and co-acting with the ports thereof, said casing having induction and eduction ports co-acting with the ports of the cylinder body, two cam-engaging elements carried by said lever, and cams carried by the casing and engaged by said two cam-engaging elements.

2. In an engine, the combination of a shaft, a cylinder body carried by said shaft and provided with a pair of straight-axis cylinders, arranged end to end and each of which is arranged substantially

perpendicular to a radius of the rotor and ported laterally for the induction and eduction of motive fluid, pistons mounted in the cylinders of said cylinder body, a lever pivoted in the cylinder body and connected to said pair of pistons, a casing enclosing said cylinder body and co-acting with the ports thereof, said casing having induction and eduction ports co-acting with the ports of the cylinder body, two cam-engaging elements carried by said lever, and cams carried by the casing and engaged by said two cam engaging elements.

3. In an engine, the combination of a shaft, a cylinder body carried by said shaft and provided with a pair of cylinders, each of which is arranged substantially perpendicular to a radius of the rotor and ported laterally for the induction and eduction of motive fluid, pistons mounted in the cylinders of said cylinder body, a lever pivoted in the cylinder body between the pair of pistons and connected to said pair of pistons and provided with forwardly and rearwardly extending arms carrying cam-engaging elements, a casing enclosing said cylinder body and co-acting with the ports thereof, said casing having induction and eduction ports co-acting with the ports of the cylinder body, a cam carried by the casing and co-acting with the forward cam-engaging element of the lever, and a cam carried by the casing and co-acting with the rearward cam-engaging element of the lever.

4. In an engine, the combination of a shaft, a cylinder body carried by said shaft and provided with a pair of straight axis cylinders, each of which is arranged substantially perpendicularly to a radius of the rotor and ported laterally for the induction and eduction of motive fluid, pistons mounted in the cylinders of said cylinder body, a lever pivoted in the cylinder body between the pair of pistons and connected to said pair of pistons and provided with forwardly and rearwardly extending arms carrying cam-engaging elements, a casing enclosing said cylinder body and co-acting with the ports thereof, said casing having induction and eduction ports co-acting with the ports of the cylinder body, a cam carried by the casing and co-acting with the forward cam-engaging element of the lever, 105 and a cam carried by the casing and co-acting with the rearward cam-engaging element of the lever.

In witness whereof, I Arthur J. Paige have hereunto set my hand at Highland 120 Park, Michigan, this 5th day of June, A. D. one thousand nine hundred and twenty-three.

ARTHUR J. PAIGE.
